UNITED STATES PATENT OFFICE.

JAMES O. CUNNINGHAM, OF INDIANAPOLIS, INDIANA.

CARBURETER.

1,382,063.

Specification of Letters Patent. Patented June 21, 1921.

Application filed March 23, 1920. Serial No. 368,080.

To all whom it may concern:

Be it known that I, JAMES O. CUNNINGHAM, citizen of the United States, residing at Indianapolis, in the county of Marion and State of Indiana, have invented certain new and useful Improvements in Carbureters, of which the following is a specification.

The present invention relates to a fuel feeding device for internal combustion engines, and has for its object to provide an invention of this character which embodies novel features of construction whereby the partial vacuum of the intake manifold may be utilized to lift the liquid fuel from a tank located at a low level to a carbureter located at a higher level, thereby avoiding the necessity of using some auxiliary apparatus such as a vacuum tank for this purpose.

Further objects of the invention are to provide a fuel lifting device of this character which can be embodied in the construction of a float feed carbureter without interfering with the proper functioning of the carbureter, which will operate effectively at all engine speeds, and which will insure an adequate supply of gasolene or other liquid fuel to meet the requirements of the engine under all working conditions.

With these and other objects in view the invention consists in certain combinations, arrangements and associations of the parts, which will more fully appear as the description proceeds, the novel features thereof being pointed out in the appended claims.

For a full understanding of the invention reference is to be had to the following description, and accompanying drawings, in which:—

Figure 1 is a vertical sectional view through a carbureter constructed in accordance with the invention.

Fig. 2 is a horizontal sectional view through the same, taken on the line 2—2 of Fig. 1 and looking in the direction of the arrows.

Fig. 3 is a similar view, taken on the line 3—3 of Fig. 1 and looking in the direction of the arrows.

Figs. 4 and 5 are detail views of the mouth piece for the suction tube and the air deflector which is associated therewith.

Corresponding and like parts are referred to in the following description and indi-

cated in all of the views of the drawing by like reference characters.

One possible embodiment of the invention has been illustrated by the drawing and will be described for the purpose of explaining the general idea of the invention, although it will be understood that many modifications and changes can be made without departing from the spirit and scope of the invention. The carbureter shown is of the compound nozzle type, and the construction and operation of the carbureter will merely be explained briefly, since carbureters of this type are well known in the art and no claim to novelty is based thereon. The float chamber 1 is closed at its top by a cover plate 2, and communicates at its base with a passage 3 which leads to the base of a main jet 4. A cap jet 5 surrounds the main jet and communicates at its lower end with a passage 6 leading laterally from a well 7 which is shown as formed in the body of the carbureter intermediate of the float chamber 1 and mixing chamber 8.

The lower end of the well 7 communicates through a restricted port 9 in a compensator plug 10 with the passage 3, so that under normal conditions the liquid fuel will rise in the well until it reaches the level of the fuel in the float chamber. Removable plugs 11 at the bottom of the carbureter enable access to be had to the compensator plug 10 and main jet 4 when such is necessary. A choke or "venturi" is fitted in the mixing chamber 8 and operates in the well known manner to produce a rotative or spiral motion of the air which is drawn into the mixing chamber through the air intake 12. The usual throttle valve 13 is arranged in the upper end of the mixture passage and operates in the usual manner to govern the speed of the engine by controlling the supply of explosive mixture thereto.

The level of the liquid fuel within the float chamber 1 is automatically controlled by the action of a float 14, said float having a guide stem 15 at the lower end thereof, and being provided at its upper end with a needle valve 16 which controls the entrance of liquid fuel into the float chamber through a fuel inlet 17 at the top thereof. The upper end of the well 7 communicates through a priming opening 18 with the mixture passage of the mixing chamber at a point ad-

adjacent the throttle valve 13, and the effective size of this priming opening is controlled by a needle valve 19. When starting the engine, the throttle valve is only partially 5 opened, and fuel will be drawn through the priming opening 18 to provide a rich starting mixture.

When the engine is in operation the quantity of fuel that can be drawn through the 10 cap jet 5 is limited by the flow of fuel through the restricted port 9 after the initial supply of fuel in the well 7 has been exhausted. The result is that at low engine speeds 15 the spray from the cap jet 5 is stronger than that from the main jet 4, although as the engine gains speed and the suction becomes greater, the main jet 4 gains in strength while the cap jet 5 becomes weaker. Both jets are in action at all speeds, and 20 the defect of one jet, starting poor and growing richer until it is about right at high speed, is compensated by the defect of the other jet which starts too poor and keeps growing poorer. One supplements 25 the other so that at every motor speed there is a substantially constant ratio of air and gasoline to supply efficient combustion.

A suction pipe 20 leads from an opening 21 in the top of the float chamber to a port 22 arranged at one side of the mixture passage of the mixing chamber 8 at a point below the throttle valve 13. A plate 23 which, as indicated by Fig. 5, may be substantially V shaped in formation, is arranged in the 35 mixture passage so as to provide an upwardly opening flared or fan shaped mouth for the suction pipe 20. The upper end of the mouth terminates at a point adjacent the upwardly swinging edge of the throttle valve when the 40 latter is at its closed position, and the mouth is curved to conform to the curvature of the walls of the mixing chamber. Associated with this mouth plate 23 is an inclined air deflector plate or fin 24. The inclination of 45 this air deflector plate 24 will cause a high velocity jet of air or fuel mixture to pass the upper edge of the mouth plate 23 when the engine is in operation, and this will operate in the well known manner to produce a partial 50 vacuum in the suction pipe 20. This partial vacuum will be transmitted to the float chamber 1 where it will operate to lift the liquid fuel from a tank located at a low level and automatically draw the fuel into the 55 float chamber as permitted by the float valve to maintain the fuel within a float chamber at a constant level.

The top of the float chamber is provided with an air inlet 25 which is controlled by a 60 check valve 26. This check valve is normally held in a closed position by a spring 27, and the tension of this spring can be governed by screwing the cap piece 28 of the check valve down or up on the nipple of the air inlet opening. This check valve controls the de-

gree of vacuum that can be produced within the float chamber, since as soon as a predetermined degree of vacuum has been produced within the float chamber the check valve will automatically open and permit 70 atmospheric air to enter the float chamber until the vacuum drops to the proper point. This prevents the vacuum in the float chamber from becoming as perfect or strong as the vacuum in the mixing chamber 8. In 75 other words, there will always be a stronger vacuum in the mixing chamber than in the float chamber, so that there will be no possibility of the partial vacuums in the two chambers counterbalancing each other and 80 preventing the feeding of fuel from the float chamber to the jets or nozzles. At the same time a vacuum of sufficient intensity to lift the liquid fuel from a tank at a lower lever and draw it into the float chamber, as is necessary to meet the requirements of the engine, 85 is maintained in the float chamber. This vacuum is even produced at low speeds, since the air deflector plate or fin 24 of the mouth plate 23 will produce suction through the 90 pipe 20 when the throttle valve 13 is practically closed for the idling speed of the engine. The gasoline or liquid fuel is thus lifted from a tank at a lower level and automatically fed to the float chamber of the carburetor as is 95 necessary, without the necessity of using any auxiliary apparatus such as the conventional vacuum tank for lifting the fuel.

Having thus described my invention, what I claim as new is:—

1. The combination with a carburetor formed with a mixture passage, a suction pipe communicating with the mixture passage, fuel lifting means associated with the suction pipe, and air deflecting means arranged within the mixture passage of the carburetor for directing a high velocity jet of air across the mouth of the suction pipe. 100

2. The combination with a carburetor formed with a mixture passage, of a suction pipe 110 communicating with the mixture passage, fuel lifting means associated with the suction pipe, a mouth piece for the suction pipe, and an inclined air deflector arranged within the mixture passage of the carburetor 115 and positioned to direct a jet of air across the orifice of the mouth piece.

3. The combination with a carburetor formed with a mixture passage, of a throttle valve, a suction pipe leading from the mixture passage, fuel lifting means associated with the suction pipe, a mouth piece for the 120 suction pipe, said mouth piece having an orifice which is positioned adjacent the throttle valve, and an inclined air deflector arranged within the mixture passage and associated with the mouth piece to direct a jet of air across the orifice thereof. 125

4. The combination with a carburetor having a float valve chamber and a mixture 130

passage, of a suction pipe leading from the mixture passage to the float valve chamber, a mouth piece for the suction pipe at the end thereof which communicates with the mixture passage, an inclined air deflector arranged within the mixture passage and associated with the mouth piece to deflect an air jet across the orifice thereof, and means for automatically preventing the partial vacuum in the float chamber from becoming 10 as great as the partial vacuum in the mixture passage.

In testimony whereof I affix my signature.
JAMES O. CUNNINGHAM
